UNITED STATES PATENT OFFICE.

HENRY Z. COBB, OF PROVIDENCE, RHODE ISLAND, ASSIGNOR TO THE SHOE HARDWARE COMPANY, OF WATERBURY, CONNECTICUT, A CORPORATION OF CONNECTICUT.

MULTIPLE-FASTENING DEVICE.

Application filed March 29, 1924. Serial No. 702,719.

This invention relates to separable fasteners, and more particularly, multiple-operated types thereof in which an entire series of fastening elements is engaged by movement of a slider lengthwise the row of fasteners.

It aims to provide a construction in which the slider may be employed to successively inter-engage a series of snap fastening elements by movement thereof in one direction, and then, if desired, returned to its starting position, to present a smart appearance, simulating for instance the appearance of a small buckle at the bottom of the opening on a garter. It also aims to provide a construction and mounting of the snap fastening elements which may be operated reliably and without jamming, by a simple form of slider which may be constructed of sheet metal at a low cost. And it further aims to provide a construction and arrangement in which the opening or separation of the fasteners may be effected manually by pulling on one of the flaps or stringers at the sides of the opening. And it aims still further, to provide a construction that is incapable of being rendered inoperative in service under the conditions that ordinarily obtain, in other words, is practically foolproof. Other objects of the invention and advantages will appear later in the detailed description of same.

With the illustrated embodiment in mind and without intention to limit more than is required by the prior art, the invention, briefly described, consists in a series of co-operating male and female elements mounted on the opposite margins of an opening in an article, which elements are adapted to be closed only by movement in one direction of a slider which is C-shaped in cross-section, the slider being movable to starting position without effect upon the inter-engaged fastening elements. Separation of the fasteners may be accomplished by a rapid ripping operation. And in one form of the invention, at least, the slider may be moved automatically as the fasteners are ripped apart. Preferably, flanges or equivalent means are provided for preventing sidewise disengagement of the slider when it is moved lengthwise a row of the fastening elements.

Embodiments of the invention are illustrated in the accompanying drawings, in which:—

Figure 1 is a plan view of a series of snap

fasteners, showing the co-operating elements thereof applied to flaps or stringers with a slider in an intermediate position;

Figure 2 is a longitudinal section illustrating the successive engagement of the snap fasteners as they pass through the slider;

Figure 3 is a transverse section, on an enlarged scale, illustrating the novel construction of the snap fasteners;

Figure 4 is a cross-section through the slider with a snap fastener appearing in closed position;

Figure 5 is a bottom plan view of the slider;

Figure 6 is a side elevation of the same;

Figures 7 and 8 are cross-sections of modified forms of male fastening elements, illustrating flanges for preventing sidewise disengagement of the slider;

Figure 9 is a plan view similar to Figure 1, showing another and the preferred form of the invention;

Figure 10 is a cross-section through the same taken through the slider;

And Figure 11 is a side elevation of the slider.

The invention is primarily intended for application to arctics, shoes, and other articles of manufacture having a slit type of opening, or placket, which is permanently closed at one end only. But the invention is not so limited and may be used for closing openings in any articles of manufacture permanently closed at one or both ends, or open at both ends, as for instance automobile curtains, tents, corsets, tobacco pouches, etc.

Referring to the drawings, 1 and 2 represent stringers or margins of an opening in an article to which are secured, by crimping or upsetting in a manner well known, or convenient, a series of fastening elements 3 and a series of co-operating elements 4. These may be of any suitable and well known construction, but are preferably of a snap-fastening type, in which the elements 3 comprise divided and resilient heads 5, which are gripped and covered by a cap 6, and constitute female elements. The co-operating elements or studs 4 comprise a ball portion 7, rising from a preferably, but not necessarily, dished base 8, connected by an offset shank or web 9 to an anchoring portion 10. The anchoring portions 10 preferably have a downwardly directed sleeve 11, which is adapted to be crimped, as indicated at 12, onto the margins or stringers 2. By thus supporting and

constructing the male or stud elements with their ball-carrying portions 8 in overhanging and spaced relation to their anchoring portions 10, a guideway 13 is defined by one of the series of elements secured to a margin or stringer 2, for the reception of the lower and pressing lip 14 of a slider 15, which is approximately C-shaped in cross-section, as shown in Figure 4, another lip 16 of which slider is adapted to engage the margins of the cap portion 6 of the female elements 3, on the second margin or stringer of the article.

The slider 15 is preferably flared when viewed in side elevation, as in Figure 6, so that in drawing it lengthwise the fasteners, they may loosely enter it at one end and then be gradually pressed together by the opposed walls 14 and 14'. See Figure 2 of the drawings. Registration (laterally) of the co-operating fastening elements of the two series is insured by the down-turned lip 16, the wall 16', and the free edge of the lower pressing lip 14. Any suitable means may be provided to grasp and operate the slider 15, as for instance the finger-piece 17, shown conventionally articulated thereto.

To insure against sidewise disengagement of the slider 15, the stud-carrying portion may be bent or flanged at one side of the studs 7, as indicated at 18 in Figure 7 of the drawings, in which case, the slider 15 desirably has the edge of its lower lip 14 correspondingly bent or flanged. Or, the same end may be attained, and with possibly greater facility in manufacture, by providing an upturned flange 19 on the anchoring portions 20 at the other side of the studs 8. The flanges 18 and 19 may be bent into position before or after the stud members have been crimped, or otherwise secured, to a margin of the opening, as convenient.

To halt movement of the slider, any suitable device may be employed at the opposite ends of the rows of fastening elements, for instance, ordinary snap-fasteners 30, whose studs are secured directly (not in overhanging spaced relation) to the body fabric or margin 2, or whose co-operating elements 31 and 32 are too large to enter the slider 15. It is to be understood, however, that all of the fastening elements on the respective flaps or margins of the opening may be made, if desired, of the same size and shape to permit bodily removal of the slider from one end of the row of fasteners at the will of the user. Preferably, however, a large stud element of the construction shown at 31 and 32, or some other suitable and convenient stop, is provided at the separable end of the opening to insure against removal of the slider, it being intended that the slider on such articles as gaiters may be moved at the will of the user to a position over or below the instep so that its operating finger-piece 17 (which may be made of any suitable de-

sign and material) may present a neat and attractive appearance, somewhat after the fashion of a small buckle.

It is to be noticed that the opposite edges of the ball-carrying portions 8 of the stud elements are preferably dished or turned upwardly transversely of the length of the row in the forms of the invention above described and as illustrated clearly in Figure 2 of the drawings, to prevent the lower lip 14 of the slider from catching or jamming in operation.

In Figures 9, 10 and 11, of the drawings, another and the preferred form of the invention is illustrated. In this embodiment, the female elements 3 and co-operating male elements 4, are of the same general construction and arrangement as previously described. The restraining flanges 19, however, are preferably, but not necessarily, formed to prevent the slider 15 from catching on their ends, as by bending the same, as indicated at 19'. The flanges 19 may be concealed by a rib 19'' formed by stitching a fold in the material of the stringer, or by vulcanization if made of rubber. In addition, in the throat or guideway 13 of the male elements 4, is located a flexible strip 40, which renders the upper wall of the guideway or throat 13 continuous. In this way, a smooth unbroken surface or abutment is presented to the pressing lip 14 of the slider 15, whose operation in service is thereby greatly facilitated. Desirably also, but not necessarily within the broadest aspects of the invention, a second flexible strip 41 is also provided parallel with the first-mentioned strip 40. Between the two strips 40 and 41, the lip 14 of the slider 15 may be positively confined and guided in its movement lengthwise the rows of fastening elements. When two flexible strips 40 and 41 are employed in conjunction with

sidewise restraining flanges, such as 19 illustrated in Figure 10, or as indicated at 18 in Figure 7, the entire device is rendered practically foolproof in service. That is to say, the slider cannot become disengaged under the conditions that are usually encountered in service, it cannot catch or jam in any manner that necessitates journeying to a mechanic or repair man with the article, and curves or bends in such articles as artics or gaiters may be negotiated by the slider 15 with certainty and facility. If the invention in this form is applied to gaiters, bending of the individual spaced apart and superimposed ball and anchoring portions of the male elements 4 is minimized by the thickness of the interposed flexible strip or strips 40 and 41. But should they be bent to the limited extent permitted by the added thickness of the one or more strips 40 and 41, subsequent operation of the slider 15 would cause the pressing lip 14 to spread or bend back the distorted male elements, the pressing lip 14, under such circumstances, functioning as

a wedge. The one or more flexible strips 40 and 41, which may be inserted to facilitate operation of the slider, are preferably made of a smooth and resilient material, such as 5 spring metal or steel.

Obviously, the pressing lip 14 might be bent at an angle so as to engage the inner edge of either or both the flexible strips 40 and 41, to prevent sidewise disengagement of the 10 slider 15, but such construction is not deemed desirable as an alternative for the flanges 18 and 19, inasmuch as there would be tendency to spring the strips out of place, and intermediate anchorage or fastening of these 15 strips is not deemed desirable. The flexible strips 40 and 41 may be variously secured at their opposite extremities and at the opposite ends of the rows of fastening elements, but preferably by simply riveting 20 them together and to the underlying stringer, as indicated at 42 and 43. By such attachment, the slider 15 is prevented from being removed, that is, it is permanently mounted on the article. Obviously, to permit bodily 25 removal of the slider 15, the upper flexible strip 40 may be secured to the overhanging portion of the endmost male element 4.

In the form of the invention illustrated in Figure 9, the slider 15 may be, and preferably 30 is, constructed as shown in Figures 5 and 6 of the drawings. If it be desired to move the slider 15 automatically without grasping it when the snap fasteners are manually pulled or ripped apart in order to open the placket, 35 a cam-lip 44 may be provided for successive engagement by the female elements 3.

It will be understood, of course, that the invention is not limited to the details of construction disclosed, which are merely illustrative of the principles underlying the invention for an understanding of whose scope 40 reference should be made to the accompanying claims.

Having thus described my invention, what 45 I claim and desire to protect by Letters Patent is:—

1. A separable snap-fastening device for 50 openings in articles comprising, a series of fastening elements secured to and overhanging one margin, a series of co-operating fastening elements on the other margin, and a device tracking the elements for inter-engaging them by movement thereof in one direction but ineffective thereon when moved in 55 the opposite direction.

2. A separable snap-fastening device for 60 openings in articles comprising, a series of fastening elements secured to and overhanging one margin in spaced relation thereto, a series of co-operating fastening elements on the other margin, and means for inter-engaging said elements to close the opening comprising a slider C-shaped in cross-section.

65 3. A separable snap-fastening device for

openings in articles comprising, a series of fastening elements secured to and overhanging one margin in spaced relation thereto, a series of co-operating fastening elements on the other margin, and a slider having opposed convergent wall-portions for pressing 70 said elements together and other wall-portions for registering the two series of elements, said slider being freely movable over the closed fastening elements. 75

4. A separable snap-fastening device for 80 openings in articles comprising, a series of fastening elements secured to and overhanging one margin in spaced relation thereto, a series of co-operating fastening elements on 85 the other margin, means for inter-engaging said elements to close the opening comprising a slider C-shaped in cross-section, and means on the first-mentioned series of fastening elements for preventing sidewise disengagement of the slider.

5. A snap-fastener for separable closures 90 comprising, co-operating and inter-engageable male and female elements, said male elements having anchoring portions and stud-carrying portions overhanging said anchoring portions and spaced therefrom, in combination with, a slider for successively operating said elements.

6. A separable snap-fastening device comprising, cooperating and inter-engageable male and female elements, said male elements having anchoring portions, stud-carrying portions overhanging the anchoring portions, and shanks at one side of said anchoring portions, in combination with, a slider for closing only said elements, said shanks preventing said slider from becoming disengaged in operation. 100

7. A separable snap-fastening device comprising, co-operating and inter-engageable rows of male and female elements, said male elements having anchoring portions and stud-carrying portions overhanging the anchoring portions, said stud-carrying portions having oppositely located bent edges 110 disposed transversely the length of the row thereof, in combination with, a slider for closing said elements having a lip and opposed wall co-operating with said lip for 115 pressing said male and female elements successively together, said lip being adapted to engage under said stud-carrying portions and to be cammed downwardly by the bent edges of said stud-carrying portions. 120

8. A separable snap-fastening device for 125 openings in articles comprising, series of stud and socket elements secured at intervals to the respective margins of an opening, one of said series of elements having anchoring portions spaced from and below its studs, a closing slider, and means located between said anchoring portions and studs of one of the series of elements for guiding the slider in its operation. 130

9. A separable snap-fastening device for openings in articles comprising, series of stud and socket elements secured at intervals to the respective margins of an opening, one of said series of elements having anchoring portions spaced from and below its studs, a closing slider, and a flexible strip below and immediately adjacent the stud elements constituting a continuous abutment and guide for the slider. 65
10. A separable snap-fastening device for openings in articles comprising, series of stud and socket elements secured at intervals to the respective margins of an opening, one of said series of elements having anchoring portions spaced from and below its studs, a closing slider, and a spring metal strip interposed between the slider and one of said series of elements for facilitating its operation. 70
11. A separable snap-fastening device for openings in articles comprising, series of stud and socket elements secured at intervals to the respective margins of an opening, one of said series of elements having anchoring portions spaced from and below its studs, a closing slider, a flexible strip below and immediately adjacent the stud elements constituting a continuous abutment for the slider, and means flanking the strip for preventing sidewise disengagement of the slider. 75
12. A separable snap-fastening device for openings in articles comprising, series of stud and socket elements secured at intervals to the respective margins of an opening, one of said series of elements having anchoring portions spaced from and below its studs, a closing slider, a spring metal strip interposed between the slider and one of said series of elements for facilitating its operation, and flanges located at one side of said stud elements for preventing sidewise disengagement of the slider. 80
13. A separable snap-fastening device for openings in articles comprising, series of stud and socket elements secured at intervals to the respective margins of an opening, one of said series of elements having anchoring portions spaced from and below its studs, a closing slider having a pressing lip, and a pair of flexible strips located between said anchoring portions and studs of one of the series of elements for engaging the opposite sides of said pressing lip and facilitating the operation of the slider. 85
14. A separable snap-fastening device for openings in articles comprising, series of stud and socket elements secured at intervals to the respective margins of an opening, one of said series of elements having anchoring portions spaced from and below its studs, a closing slider, and a pair of spring metal strips located between said anchoring portions and studs and defining a flexible guide- 90
- way for a portion of said slider whereby to facilitate its operation. 95
15. A separable snap-fastening device for openings in articles comprising, series of stud and socket elements secured at intervals to the respective margins of an opening, one of said series of elements having anchoring portions spaced from and below the studs, a closing slider, and a pair of spring metal strips in superimposed parallel relation secured only at the opposite ends of one of the series of elements and located between said anchoring portions and studs for guiding the slider in its operation. 100
16. A separable snap-fastening device for openings in articles comprising, series of stud and socket elements secured at intervals to the respective margins of an opening, one of said series of elements having anchoring portions spaced from and below the studs, a closing slider, and a pair of spring metal strips in superimposed parallel relation secured together only at their opposite extremities adjacent the ends of one of the series of elements, said strips extending beneath the elements of one series and defining a continuous resilient guideway and abutment for the slider. 105
17. A separable snap-fastening device for openings in articles comprising, a series of fastening elements secured to and overhanging one margin, a series of co-operating fastening elements on the other margin, a device tracking the elements for inter-engaging them by movement thereof in one direction but ineffective thereon when moved in the opposite direction, and means for preventing sidewise disengagement of the slider from the elements. 110
18. In a snap fastener, a male element comprising an anchoring portion, a ball carrying portion spaced from and overhanging said anchoring portion, and an offset shank connecting said portions. 115
19. A separable snap-fastening device for openings in articles comprising a series of interengageable fastening elements on each margin, and a slider tracking the elements and provided with an unobstructed converging passage acting to interengage the elements when moved in one direction and permitting movement of the slider over the engaged elements without effecting disengagement thereof. 120
20. A separable snap-fastening device for openings in articles comprising a series of interengageable fastening elements on each margin, and a slider tracking the elements and provided with an unobstructed converging passage acting to interengage said elements as they move therethrough in one direction and permitting the passage of the slider over the interengaged elements in either direction without effecting disengagement of 125

the elements, one of said series of fastening elements at least being provided with means obstructing sidewise disengagement of the slider.

- 5 21. A separable snap-fastening device for openings in articles comprising a series of interengageable fastening elements on each margin, and a slider tracking the elements and provided with an unobstructed passage

acting to interengage the elements when moved in one direction and permitting movement of the slider over the engaged elements without effecting disengagement thereof.

Signed at Providence, county of Providence, and State of Rhode Island, this 27th ¹⁵ day of March, 1924.

HENRY Z. COBB.
